United States Patent Office

Des. 180,986
Patented Sept. 17, 1957

180,986

WATER HEATER THERMOSTAT

Thomas T. Arden, Santa Ana, Henry C. Keck, Pasadena, and Wilbur F. Jackson, Compton, Calif., assignors to Robertshaw-Fulton Controls Company, Greensburg, Pa., a corporation of Delaware

Application November 21, 1955, Serial No. 38,967

Term of patent 14 years

(Cl. D52—1)

The figure is a perspective view of a water heater thermostat, showing our new design.

The opposite side of the water heater thermostat is the same in appearance as the side shown, and the rear is substantially plain.

We claim:

The ornamental design for a water heater thermostat, as shown and described.
